(57) **CLAIM**

The ornamental design for a conversion adapter for electrical connection, as shown and described.

DESCRIPTION

FIG. 1 is front elevational view of a conversion adapter for electrical connection showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, left side, top perspective view thereof;

FIG. 8 is a front, left side, bottom perspective view thereof;

FIG. 9 is a front, right side, top perspective view thereof;

FIG. 10 is a front, right side, bottom perspective view thereof;

FIG. 11 is a rear, right side, top perspective view thereof;

FIG. 12 is a rear, right side, bottom perspective view thereof;

FIG. 13 is a rear, left side, top perspective view thereof; and,

FIG. 14 is a rear, left side, bottom perspective view thereof.

The broken lines in the drawings illustrate portions of the conversion adapter for electrical connection that form no part of the claimed design.
